(57) CLAIM

The ornamental design for vase, as shown and described.

DESCRIPTION

FIG. 1 is a side perspective view of a vase, showing the new design;

FIG. 2 is a front perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken line showing of the inside surface and top and bottom edges is for illustrative purposes only and forms no part of the claimed design.

1 Claim, 8 Drawing Sheets
